UNITED STATES PATENT OFFICE.

CLARENCE W. CARTER, OF MINNEAPOLIS, MINNESOTA.

APPARATUS FOR HEATING AND TEMPERING GRAIN.

1,181,434.

Specification of Letters Patent.

Patented May 2, 1916.

Application filed July 16, 1914. Serial No. 851,303.

To all whom it may concern:

Be it known that I, CLARENCE W. CARTER, a citizen of the United States, residing at Minneapolis, in the county of Hennepin and State of Minnesota, have invented certain new and useful Improvements in Apparatus for Heating and Tempering Grain, of which the following is a specification.

My invention relates to an apparatus for heating and tempering grain, and has for its object to provide a mechanism for this purpose which shall be relatively compact, easily accessible and which will act upon the grain so as to heat rapidly and uniformly all parts of the grain passing through the machine. To this end I provide a stationary, horizontal battery of heated pipes sufficiently spaced one from another and securely held in such spaced position by means which will not obstruct the passage of grain through the machine. The grain is caused to pass over and over the pipes of this battery by means of a drum having a series of baffles thereon which rotate about the battery of pipes continually, bringing the grain to the top of said battery and dropping it upon the same, which grain rattles through striking successive pipes until it passes to the bottom, where it is again carried up and the operation repeated until the grain reaches the discharge opening at the forward end of the drum. The movement of the grain from the receiving end to the discharge end may be effected by a slight inclination of the drum; but in practice it has been found that such movement will take place without any inclination of the drum, the impingement of the kernels of grain at the receiving end upon those in advance having the effect of causing the advance grain to move slowly forward through the machine and finally to reach the discharge end thereof. My invention provides improved means for supporting and rotating this drum in relation to the means for feeding the grain into the same whereby all joints or obstructions which might cause clogging or wear of the drum are avoided.

The full objects and advantages of my invention will appear in connection with the detailed description thereof and are particularly pointed out in the claims.

In the drawings, illustrating the application of my invention in one form,—Figure 1 is a longitudinal sectional view of a heating and tempering machine embodying my

invention. Fig. 2 is a sectional elevation on line 2—2 viewed in the direction of the arrow. Fig. 3 is a sectional elevation on line 3—3 viewed in the direction of the arrow. Fig. 4 is a detail view showing the manner of capping the steam-pipes so as not to increase the diameter at the cap end.

As illustrated, I provide a frame consisting of end supports 10 and 11 rigidly secured in spaced relation by truss rods 13, 14 and 15. End support 11 is provided with an inner plate 16 and a casing 17 adjacent thereto through which runs a partition 18 dividing the interior of said casing into two chambers 19 and 20, respectively. A series of apertures are formed through end plate 16 into chamber 20, within which are seated the ends of a plurality of steam-pipes 21 which are thus placed in communication with chamber 20. Similarly, the partition 18 is provided with a plurality of apertures extending through the same into chamber 19, in which are seated the ends of a series of pipes 22 of smaller diameter than pipes 21, which pipes extend to a point adjacent the cap ends of pipes 21, as indicated at 23 in Fig. 1. The pipes 22 are thus placed in communication with the chamber 19. Steam is admitted to chamber 19 through a steam-pipe 24, which steam flows through pipes 22 to the points 23 at the ends of pipes 21, whence the steam returns through pipes 21 to chamber 20 and may be discharged through a pipe 25. The course of the steam is indicated by arrows in Fig. 1 of the drawings. By this means the pipes 21 are supplied with steam so as to heat the exposed walls of the same to the desired degree.

The portions of the pipes 21 extending from the point of inner support on plate 16 are held properly spaced from one another by means of a series of plates 26. These plates are of relatively thin metal provided with apertures only sufficiently large to permit the pipes 21 to pass through said apertures; and when the plates are positioned, as indicated in Figs. 1 and 3, upon the pipes 21, said pipes are held in the desired relative position and at the same time the plates 26 do not interfere with the operation of the cylinder or with the movement of the grain through the machine. In some instances it is contemplated that the plates 26 be turned obliquely opposite to the direction of travel of the grain through the machine, as indicated in dotted lines at 27, thus acting to

somewhat retard the movement of grain through the machine. The end spacing plate 28 is, as shown in Fig. 1, turned obliquely in the opposite direction and has a portion 29 extended below the lowermost pipes 21 for a purpose which will be herein-after given. The support 10 is provided with an end plate 30 having a central cut-out circular portion 31 which is fitted with an inwardly-turned closure 32, as clearly shown in Figs. 1 and 2. Two of the pipes 21 have extended ends 33 which pass through apertures in the closure 32, thereby supporting the rear end of the entire battery of pipes.

It will thus be seen that the battery of pipes, by reason of the spacing plates 26 and 28 and the support from pipe ends 33, is properly held in a suspended or floating manner between supports 10 and 11 with no portion operating to interfere with the passage of grain through the machine or the operation of the surrounding cylinder, which will now be described. This cylinder comprises an inner skin 34, an outer skin 35, a wooden envelop 36 adjacent the outer skin and a filler 37 of insulating material. The inner and outer skins are preferably formed of sheet metal. Bolted to the cylinder by bolts having countersunk heads, as indicated at 38 in Fig. 1, adjacent the front and rear ends of said cylinder, are rings 39 and 40, respectively, which rings rest upon rollers 41 and 42, journaled on truss rods 14 and 15. Bolted to the end of ring 40 so as to close the rear end of the cylinder is a circular disk 43 having a central circular aperture closely surrounding the inturned header 32, as clearly indicated in Figs. 1 and 3. Upon the ring 40 is formed a spur gear 44 which meshes with a pinion 45 driven from any desired source of power. It thus appears that the cylinder rests and turns upon the rollers 41 and 42, forming with its end 43 a closed joint with the comparatively small header member 32, which joint is so situated that grain or dust cannot enter so as to materially affect the character of the joint even after a long period of use. The forward end of the cylinder is, as indicated at 46, projected within the open mouth of a cylindrical casing 47 rigidly secured to plate 16 of support 11, said casing 47 being provided with a discharge spout 48 at the bottom thereof. A feed spout 49 extends in a downwardly-inclined direction through the header member 32. Some of the bottom pipes 21, as indicated at 50, are somewhat shortened in front of the discharge opening from spout 49, providing a grain-receiving space 51. The depending portion 29 of the spacing plate 28 forms a baffle across this grain-receiving portion 51 against which the grain impinges, thereby causing it to rebound and preventing its forward flow

through the cylinder under the momentum of its feed into the same. A plurality of backwardly-turned flights 52 secured to the inner wall 34 of the cylinder provide a series of pockets 53, which, as the cylinder is revolved, carry the grain to the upper part thereof and have the effect of discharging the grain so carried across the entire upper portion of the battery of pipes 21. The spacer plate 28 is obliquely turned in a forward direction, which has the effect of forwarding a little more rapidly than otherwise would be the case the grain carried around by the cylinder which has just been received from the feed pipe 49. This prevents an undue accumulation of grain at the feed end of the cylinder and any tendency to clog which might otherwise result. To further obviate any tendency of clogging at the feed end of the cylinder, I provide a special capping device for the pipes 21, which is indicated in detail in Fig. 4. These pipes have the end portion 54 forged down to a sufficiently smaller diameter, so that when threaded the portion 54 will receive a threaded cap 55, whose outside diameter is the same as that of pipe 21. The spaces between the caps 55 are, therefore, in all respects the same as the spaces between the pipes 21.

The advantages of my invention will readily be apparent, and its mode of operation has been clearly indicated in connection with the detailed description of the parts. Steam having been admitted through pipe 24 and passing in the described manner through pipes 21 until said pipes are sufficiently heated, the cylinder will be rotated at the desired speed and grain will be fed into the same through spout 49. The incoming stream of grain will strike against the baffle portion 29 of plate 28 and be received from the portion 51 into the rear portions of compartments 53 between flights 52. As the grain bounds backward from baffle 29 it is restrained by the plate 43, closing the end of the cylinder. This plate is substantially flush with the inner surface of the projecting closure member 32, so that as the grain is carried upward by the flights it will pass the joint between plate 43 and member 32 without any tendency to enter said joint or to retard the operation of the device. As the grain is discharged from the flights over the top of the battery of heated pipes a major part of that which is carried up at the rear end of the flights will be forwarded by the obliquely-extended plate 28, so that there will be no tendency to clog the receiving end of the cylinder. As above stated, the cylinder will either be very slightly inclined from the rear to the front or be perfectly level, and the forwarding of the grain from the receiving spout 49 to the discharge spout 48 is caused by the impingement of the grain-

itating kernels of the grain at the advance end of the sheet against those coming on from the feed end which will have the effect of causing the sheet of grain to advance slowly along the cylinder and battery of heated pipes until the discharge spout 48 is reached. Each kernel of grain will thus be caused to pass through the battery of pipes hundreds of times, and at each time the kernel of grain will strike and roll along the walls of a large number of the heated pipes of the battery. This results in all parts of the grain contacting many times with the heated pipes, and consequently an absolutely uniform heating and tempering of the grain.

If desired, the support 10 may be made adjustable vertically, so that by increasing or decreasing the inclination of the cylinder, the rate of feed through the heater may be varied to meet varying conditions of grain or character of flour being ground. This is accomplished by providing a worm screw 90 threaded into a support 91 in end casting 10 which engages with a fulcrum 92 set upon 25 the floor and will lift the end of the machine the desired amount.

I claim:

1. A grain heater comprising a frame having end walls, a battery of radiation 30 pipes supported solely from said end walls, means for receiving grain and delivering the same repeatedly at the top of the battery of pipes so as to cause the grain to flow through and around said pipes, and a plurality of plates each independent of the frame and having a series of apertures through which the several pipes of the battery are passed for holding said pipes in proper relative position, one of said plates 35 being extended to form a baffle in the path of the incoming stream of grain.

2. A grain heater comprising a frame having end portions, a battery of pipes all of which are directly supported at one end by 45 one of said end portions, and means independent of the frame for holding said pipes in proper relative position, the other end of said battery of pipes being supported from the other end portion by a portion only of 50 said pipes.

3. A grain heater comprising a frame having end portions, a battery of pipes all of which are directly supported at one end by one of said end portions, and means independent of the frame for holding said pipes in proper relative position, the other end of said battery of pipes being supported from the other end portion by some 55 of the pipes at the approximate center of the battery.

4. A grain heater comprising a frame having end portions, a battery of pipes all of which are directly supported at one end by one of said end portions, and means independent of the frame for holding said pipes

in proper relative position, the other end of said battery of pipes being supported from the other end portion by the two approximately central pipes of the battery.

5. A grain heater comprising a frame 70 having end walls, one of said end walls being provided with a circular centrally-disposed aperture, a closure member in said aperture having a cylindrical surface extended inside of said end wall, a battery 75 of radiation pipes supported by said closure and the other end wall, a cylinder mounted for rotation about said pipes, and a wall secured to one end of said cylinder having an opening with its edges surrounding and 80 engaging said cylindrical surface of the closure whereby the rotatable wall of the cylinder and the closure completely close the end of the cylinder.

6. A grain heater comprising a frame 85 having end walls, one of said end walls being provided with a circular centrally-disposed aperture, a closure member in said aperture having a cylindrical surface extended inside of said end wall, a battery of radiation 90 pipes supported by said closure and the other end wall, a cylinder mounted for rotation about said pipes, a wall secured to one end of said cylinder having an opening 95 with its edges surrounding and engaging said cylindrical surface of the closure whereby the rotatable wall of the cylinder and the closure completely close the end of the cylinder, and means extending through said closure for feeding grain into the cylinder. 100

7. A grain heater comprising a frame having end walls and longitudinal truss rods rigidly securing said end walls in fixed relative position, a battery of heated pipes supported in horizontal position from said end walls, sets of rollers journaled on said truss rods, a grain-moving cylinder surrounding said pipes and supported upon said rollers, and means to turn said cylinder on the rollers.

8. A grain heater comprising a frame having end walls and longitudinal truss rods rigidly securing said end walls in fixed relative position, a battery of heated pipes supported in horizontal position from said end walls, sets of rollers journaled on said truss rods, a grain-moving cylinder having cylindrical rings for supporting said cylinder upon said rollers and comprising tracks upon which the cylinder may be turned, and means for turning the cylinder. 110

9. A grain heater comprising a frame having end walls, one of said end walls being provided with a steam chamber, a battery of pipes the ends of which are directly 125 supported by said last-named end wall and in communication with said steam chamber, means for holding said pipes in properly spaced relation, said pipes being supported at their other ends from the other end wall, 130

and caps closing said last-named ends of the pipes, said caps being of the same diameter as the pipes to provide full spaces between the cap ends of the pipes.

- 5 10. A grain heater comprising a frame having end walls, a battery of radiation pipes supported in fixed approximately horizontal position from said end walls, means for receiving grain and delivering 10 the same rapidly at the top of the battery of pipes so as to cause the grain to fall through

and around such pipes, means independent of the end walls and carried by the pipes for holding the several pipes in proper relative position, and means to raise or lower 15 one of said end walls.

In testimony whereof I affix my signature in presence of two witnesses.

CLARENCE W. CARTER.
